COMBINED LAMP HOOD AND SUPPORT THEREFOR FOR INFANT INCUBATORS

Jack H. Schwartz, Shaker Heights, Ohio, assignor to
National Biological Corporation, Mayfield Heights,
Ohio, a corporation of Ohio

Filed Dec. 11, 1968, Ser. No. 14,903

Term of patent 14 years

Int. Cl. D24—02; D26—02
U.S. Cl. D83—1

FIG. 1

FIG. 2

FIG. 3

FIG. 4

FIG. 5

FIG. 1 is a view in front elevation of a combined lamp hood and support therefor for infant incubators embodying the design of my invention.

FIG. 2 is a view in rear elevation of the design shown in FIG. 1.

FIG. 3 is a view in side elevation of the design shown in FIG. 1, as viewed from the right side thereof.

FIG. 4 is a view in side elevation of the design shown in FIG. 1, as viewed from the left side thereof.

FIG. 5 is a top plan view of the design shown in FIG. 1.

I claim:

The ornamental design for a combined lamp hood and support therefor for infant incubators, substantially as shown.
